WEATHER STRIP

Elmer D. Barringer, Cleveland, Ohio

Application August 2, 1933, Serial No. 683,389

7 Claims. (Cl. 20—69)

This invention embodies novel improvements in weatherstrip constructions of the class particularly designed for use upon outwardly opening casement windows.

5 An essential object of the invention has been to design weatherstrip means of the class set forth embodying provisions for effectively preventing the entry of water, air and/or foreign matter between the sill portions of a window, and 10 the outwardly swinging casement windows mounted thereabove. So far as I am aware, prior commercial constructions in use today do not prevent adequately and efficiently the entrapment of water upon weatherstrip means such 15 as customarily provided between the window or windows, and the sill of the window frame in which they are mounted.

20 My invention includes, among other objects, a design of weatherstrip means of the utmost simplicity of construction, as regards the weatherstrip parts themselves, and one in which the method of applying the weatherstrip means to the sill and to the window parts is greatly simplified so as to facilitate installation.

25 Another feature of my invention resides in the formation of the window strip member in such a manner as to cooperate with the sill strip member to afford an effective double sealing action between the parts.

30 The foregoing, with other objects appertaining to the detailed structure of my invention, are achieved by the preferred forms of the invention that are illustrated in the accompanying drawing, in which:—

35 Figure 1 is a transverse sectional view of my weatherstrip construction, showing one adaptation of the invention wherein the sill weatherstrip member is preferably an extruded structure.

Figure 2 is a sectional fragmentary perspective 40 view of the window strip member according to the form of the invention of Figure 1.

Figure 3 is a view similar to Figure 2, but showing the sill weatherstrip member.

45 Figure 4 is a view similar to Figure 1, illustrating a modification of the invention in which the sill member of the weatherstrip means is made of sheet metal, a modified adaptation of the construction of Figures 1 to 3 inclusive.

Figure 5 is a view similar to Figure 4, showing 50 still another modification of my invention.

Figures 6 and 7 are perspective views like Figures 2 and 3, but showing the sill weatherstrip members of Figures 4 and 5 respectively.

Referring to Figure 1 of the drawing, A denotes 55 the sill of a window frame, or the like, said sill

being equipped with the stop strip B after the customary manner, and the window C illustrated, being of the casement type adapted to swing outwardly in opening, and to the position of Figure 1, when closed.

5 Mounted upon the sill A at the corner established by the juncture between the sill A and the stop strip B, is the sill weatherstrip member 1, the same comprising a base portion, having a vertical or upwardly extending wall 2, from which outwardly projects a sealing flange 3. The sealing flange 3 is arranged to cooperate with the window sealing member which comprises the attachment portion 4 secured by nails or other fastenings means 5 to the inner side of the window and preferably counter-sunk so as to lie flush with said inner side and to avoid providing an obstruction of the close fitting contact of the lowest portion of the window, with the stop strip B. The attachment portion 4 of the window strip is formed with a U-shaped flange comprising an upper portion 6 and a lower portion 7, these portions 6 and 7 providing sealing elements above and below, respectively, to the sealing flange 3. For stiffening the free edge of the U-shaped member comprising the parts 6 and 7, the metal of said edge is folded upon itself, as shown at 8, by being bent outwardly upon itself so that the top portion of the bend lies flat against the underside of the flange 3.

20 The base portion of the sill strip 1 may be screwed or otherwise fastened to the sill A; and this portion of said sill strip is preferably inclined at a slight angle downwardly in relation to the wall or vertical portion 2, the inclination 25 being purposeful in that it prevents entrapment of any water or foreign matter that might pass between the window and sill strips in the use of the invention. Such water by the construction set forth, will freely flow outwardly and downwardly into and from the space between the bottom edge portions of the window or windows C and the sill A.

30 For facilitating the effective securing of the sill strip 1 in position, I preferably form a sharp 45 inwardly extending lip 3a in substantially the horizontal plane of the upper side of the flange 3 and adapted to bite into the surface of the stop strip B. Likewise at the lower outer edge of the base of the sill strip 1, I provide a similar lip 1a 50 adapted to be pressed into and thus bite into the upper surface of the sill A, to assist in properly positioning the sill strip in relation to the parts A and B.

35 In the modification of my invention shown in 55

Figures 4 and 6, the sill strip 9 is made of sheet metal formed with a biting lip 10 similar to 1a previously set forth and bent upwardly to provide the vertical wall portion 11, thereupon being folded outwardly with a U-shaped fold 12 to provide the horizontal flange that corresponds with the flange 3 of Figure 1 construction. In this form of my invention the free edge 12a of the U-flange 12 is designed to contact with the stop strip B as seen in Figure 4, in order to afford a water seal action, the lip 10 being engaged with the sill A in the manner of engagement with the lip 1a, as shown in Figure 1. In the construction of Figure 4, the sealing flange 12 is slightly yieldable and its edge 12a projects a short distance beyond the vertical plane of the wall portion 11 so as to ensure the desired sealing contact of the part 12a with the stop B. The pressure downward on the resilient base portion 9 by the sill attaching fastenings is effective to maintain the said contact of the part 12a.

Now in Figures 5 and 7, I illustrate a construction which is similar to those previously described as to the general parts, but essentially similar to the construction of Figures 4 and 6 in that the sill strip comprises practically the same parts as the Figures 4 and 6 construction.

Thus, in Figure 5, it will be seen that the U-shaped sealing flange 13 of the sill strip is provided with a vertical sealing flange 14, parallel with the vertical portion 15 that corresponds with the wall 2 of the construction in Figure 1. The sealing flange 14 is adapted to slide vertically on the stop strip B, and is, therefore, capable of permitting the adjustment vertically of the sill flange 13 to the location of the window strip means comprising the U-shaped sealing member, or flange 6, which is employed in all of the various modified forms of my invention.

It is notable that in the mounting of the sealing members of my weatherstrip means, as described in reference to each construction presented above, that the sealing members of the window and sill weatherstrips are received in a rabbeted portion or space 16 provided by the cutting away of the inner lower corner edge, so to speak, of the window or windows C. In other words, the rabbeted portions 16 of the window C receive practically speaking the parts 3, 6, 7 and 2 of the weatherstrip construction of Figure 1, and the corresponding parts of the weatherstrip constructions of the modified forms of my invention.

From the foregoing, it will be apparent that the operation of installation of the parts of my weatherstrip means is exceedingly simple, it only being necessary to provide on the lower edge portions of the window the rabbeted portion 16 and the very shallow groove or recess that is designed to receive the part 4 comprising the attachment portion of the window sealing member of my invention. In so far as the general cooperation of the parts are concerned, it is evident that this cooperation is much the same in reference to both the extruded metal form of sill strip illustrated in Figures 1 and 3, and the sheet metal forms of said sill strip illustrated in Figures 4 to 7, inclusive.

While I have described my invention and claimed it as used in conjunction with outwardly opening casement windows, I do not wish to be limited only to such specific application for the construction set forth may be employed in equivalent places. Thus my weatherstrip structure is susceptible of use on the swinging or free vertical edge portions of inswinging and outswinging

casement windows as well as on the sill edges, so to speak, and such disposition is contemplated within the purview of the invention and the appended claims. In the latter construction, the so-called sill strip would either be applied to the part of the window carrying the main weatherstrip part, or applied to an intermediate stop or bar provided between the edges of two coacting windows. The sill strips described are main strips, and the window carried strips are complementary strips as readily evident.

Having thus described my invention, what I claim as new and desire to secure by Letters Patent of the United States, is:—

1. In weatherstrip construction for outwardly opening casement windows, the combination with a sill having the usual upwardly projecting stop strip, and a casement window mounted to co-operate with said sill and stop strip, of weatherstrip parts including a sill strip having a base portion secured to the upper surface of the sill adjacent to the corner provided by the juncture of the sill and the stop strip, said base portion being formed with an upwardly and vertically extending wall portion from which projects laterally and outwardly away from the vertical face of the stop strip a sealing flange spaced from the base portion, said vertically extending wall portion abutting with the outer side of the stop strip, the lower corner portion of the window at its inner side being rabbeted to provide a space for receiving said wall and flange portions of the sill strip, and a window strip carried by the window and comprising an attachment portion secured to the window, with a U-shaped sealing member projecting from said attachment portion within the upper part of the rabbeted portion of the said window, said U-shaped sealing member being adapted to receive the sealing flange of the sill strip, the sill strip being formed with an inwardly extending lip embedded in the stop strip and disposed about in the plane of the upper surface of the sealing flange, and the lower outer edge of the base portion of the sill strip being formed with a downwardly projecting lip to be embedded in the sill.

2. In weatherstrip construction as described, a window frame, a main strip comprising a base attaching portion affixed to a portion of the window frame, and having a laterally bent wall from which projects a sealing flange in the direction of the attaching portion and spaced therefrom, a window having a corner edge recess or rabbet, and a complementary strip on the window consisting of an attaching portion and a lateral sealing flange of U-form to receive the flange of the main strip, the flange and wall portions of the main strip being received in said rabbet of the window when the latter is closed, a stop on the frame, the main strip being made of sheet metal formed into the base attaching portion, bent to form the wall portion, and then bent upon itself to provide the sealing flange, the free edge of said flange sealingly engaging edgewise the stop on the frame.

3. In weatherstrip construction as described, in combination, a window frame, comprising a sill A and a stop member B, an outwardly swinging casement window C, and sealing means between said parts, comprising a sill strip having a base supported by the sill A and formed with an upwardly and vertically extending wall portion closely abutting the stop B, and an outwardly extending sealing flange, said sill strip being provided with a portion substantially in the plane of the upper surface of said flange positively en-

gaging with sealing effect against the stop strip B, and sealing means carried by the window C cooperating with the flange aforesaid of the sill strip mentioned.

5. In weatherstrip construction as described, in combination, a window frame, comprising a sill A and a stop member B, an outwardly swinging casement window C, and sealing means between said parts, comprising a sill strip having a rigid base supported by the sill A and formed with an upwardly and vertically extending wall portion closely abutting the stop B, and an outwardly extending sealing flange, said sill strip being provided in substantially the plane of the upper surface of said flange with a sealing edge positively engaged with the adjacent side of the stop grip B to prevent water from passing down between the vertical wall portion of the sill strip and thus entering between the sill strip and the stop B and the sill A, together with sealing means carried by the outwardly swinging casement window C and cooperative with the flange of the sill strip.

5. In weatherstrip construction, in combination, a window frame, comprising the sill A and the stop member B arranged at an angle thereto, an outwardly swinging casement window mounted to swing over the sill A and having its inner portion to abut with the stop B, the said sill A being downwardly inclined in an outward direction, a sill strip mounted on the sill A and comprising a downwardly inclining rigid base portion and formed at its inner edge with an upwardly projecting wall extended outwardly at its upper portion to provide a laterally projecting flange, the said flange being formed at its inner edge adjacent to the stop B with a sealing edge having sealing contact with the stop B, the lower inner edge of the casement window C adjacent to the angle between the sill A and the stop B being rabbeted to provide a recess and a sealing strip carried by the window C mounted in said recess and comprising an approximately U-shaped sealing member to engage the flange of the sill strip aforesaid, the sill strip being made of sheet metal and its base wall and flange being bent from a continuous piece of such metal, the flange comprising a U-fold of the metal, the upper inner edge of which provides the sealing edge in contact with the stop B, the sealing strip carried by the window comprising an attaching portion secured to the window.

6. In weatherstrip construction, in combination, a window frame, comprising the sill A and the stop member B, arranged at an angle thereto, an outwardly swinging window mounted to swing over the sill A and having its inner portion to abut with the stop B, the said sill A being downwardly inclined in an outward direction, a sill strip mounted on the sill A and comprising a downwardly inclining base portion and formed at its inner edge with an upwardly projecting wall extended outwardly at its upper portion to provide a laterally projecting flange, the said flange being formed at its inner edge adjacent to the stop B with a sealing edge having sealing contact with the stop B, the lower inner edge of the casement window C adjacent to the angle between the sill A and the stop B being rabbeted to provide a recess and a sealing strip carried by the window C mounted in said recess and comprising an approximately U-shaped sealing member to engage the flange of the sill strip aforesaid, the sill strip being made of sheet metal and its base wall and flange being bent from a continuous piece of such metal, the flange comprising a U-fold of the metal, the upper inner edge of which provides the sealing edge in contact with the stop B, the sealing strip carried by the window comprising an attaching portion secured to the window.

7. As a new article of manufacture, a sill strip for outwardly swinging casement windows comprising an outwardly and downwardly inclined base formed at its outer lower edge with a biting lip to be embedded in a sill, the said base being extended upwardly at its inner edge to provide a vertical wall and outwardly at the upper end of the vertical wall to provide a relatively horizontal sealing flange, the corner portion of the sill strip formed by the juncture of the inner edge of the upper surface of the flange and the upper edge of the inner surface of the wall being projected to form a biting lip to be embedded in the outer side of a window stop for the purpose described.

ELMER D. BARRINGER.
